IMPLEMENT FOR HANDLING PRINTING FORMS

Henry J. Ulmer, Ramsey, N.J.

Application January 10, 1947, Serial No. 721,395

4 Claims. (Cl. 101—368)

1

This invention relates to the printing art and especially to the operation of transferring the so-called "form" from the bed of the press onto a table (as for changing the type) or reversely. The press-bed and table are frequently somewhat spaced apart and have their surfaces more or less flush with each other. The form comprises a rectangular frame or "chase" in which the sheet of type is held by so-called "quoins" or adjustable clamps interposed between each of the four sides of the type-sheet and the corresponding side of the chase. In order to pull the heavy form from the press-bed onto the table the operator enters his fingers through a slot-like space existing between one side of the chase and the type-sheet, which frequently results in his fingers being pinched or crushed between the form and the table due to their then projecting below the under surface of the form and thus opposed by the table; frequently the resulting injury to the operator is serious.

According to this invention I provide what I term a form-puller which is so constructed and its parts so formed as to adapt it to be effectively interlocked with the form directly engaging one of the quoins thereof, the implement having a handle to be gripped by the operator's hand and which, when the implement is in operative state, is positioned well and hence safely above the form.

In the drawing,

Fig. 1 is a fragmentary plan view of a press-bed and table and a form on the press-bed to be shifted onto the table by the implement, appearing as viewed in plan;

Fig. 2 is mainly a section on line 2—2, Fig. 1, and on a larger scale;

Fig. 3 is an elevation of the implement as seen from the right in Fig. 2; and

Figs. 4 and 5 are respectively an end view of a quoin and a section of the latter on line 5—5, Fig. 1.

The form comprises the usual frame or chase 1, the sheet of type 2 within the chase (they being as usual rectangular as would appear were each shown in full), and the usual quoins (to be described) at least two of which usually occupy a slot *a* existing between any margin of the type-sheet and the corresponding side of the chase. Each quoin or clamp comprises a pair of elongated wedges 3 which, as assembled, have outer planiform sides 3a and are each formed at the inner side thereof with a longitudinal median tongue 3b, the tongue of either wedge being engaged in a groove 3c of a riser 3d of the other

10 wedge and each having at each side of its tongue a row of teeth 3e, the teeth of both wedges being adapted to be engaged by a rotary key (not shown) for displacing them lengthwise in opposite directions relatively to each other. A suitable number of the quoins being positioned in each slot, by the key they are made to exert wedging action on the type-sheet and chase so that the resulting unitary structure constituting the form is produced.

At A is the bed of the press and at B is the table onto which the form is to be displaced.

(In Fig. 1 the sheet of type is shown only in diagrammatic outline, the type being individually delineated, however, in Fig. 2.)

The form-puller of this invention is formed according to the example shown as follows:

There is a block 4 which in plan is oblong and has its bottom surface perpendicular to its upright sides. A circumferential groove 4a is formed in the block in parallel relation to said bottom surface and it provides an upwardly facing shoulder 4b.

Extending downwardly into the block is a 25 stem 5 forming a handle and which is in threaded engagement therewith and may be rotated therein. At the free end of the stem is a bar 6 forming a handle proper extending transversely of the upright threaded end portion of the stem, the latter being preferably bent, as at 30 5a, substantially at a right angle and thus appearing T-shaped in plan.

On the threaded portion of the stem is screwed a lock-nut 7, here of the winged type. It is to 35 serve releasably to bind the stem to the block against rotation.

Whereas any slot *a* may vary in width, wherefore each quoin is constructed so as to be operative on the wedge-like principle, the spacing (to be referred to) at *a'*, determined by the dimension of a riser 3d, is of course invariable whatever may be the adjustment of the quoin. But frequently a slot *a* may exist of such width that by no adjustment would a quoin having given dimensions, such as those shown in the present drawing, be serviceable, wherefore the operator usually has available another quoin of small size, with the consequence, of course, that the spacings *a'* of the two quoins are unequal.

Having these circumstances in mind, the block and stem of the present implement are to be secured together by the lock-nut so that the bar 6 may be approximately parallel with either the transverse axis or the longitudinal axis of the block, depending on how the block is enterable

2

to the available space a' existing between a projection such as $3x$ of a quoin and a surface of the form opposed to such projection and, when such entering is effected, on whether or not an effective interlock between the form and form-puller may be accomplished by the shoulder $4b$ engaging the tongue of such projection. In Figs. 1 and 2 in view of the size of the quoin shown the block has been entered to such space with its transverse axis extending lengthwise of the slot a . But if the space at a' were narrower, due to resort to a smaller quoin, the block could not be entered to said space with its transverse axis so extending. In that case, since the block would have to be entered with its longitudinal axis extending lengthwise of the slot, the handle is to be adjusted 90° from its shown position, or so as to be approximately parallel to the longitudinal axis of the block, that is, by releasing the lock-nut, effecting the necessary relative rotation as between the block and handle, and resetting the lock-nut in binding position.

The implement is shown in interengaged relation to a projection $3x$ which is relatively remote from and whose tongue $3b$ projects toward the table. It might, however, be interengaged with a projection $3x$ (as at the opposite end of the quoin which adjoins the table in Fig. 1) whose tongue projects away from the table. Since the implement might be usable in one of these positions and immediately thereafter in the other it is of advantage to have the shoulder $4b$ exist at both of the long and short sides of the block.

Essential features of my invention include a block substantially oblong in plan and having an upwardly facing shoulder, as $4b$, at each of at least two upright sides of the block which adjoin each other and a stem upstanding from the block and rotative relatively thereto around an upright axis and having above the block a transversely extending handle. With the implement so constructed upon 90° rotative adjustment of the stem relatively to the block the implement can be operatively engaged in such a space as a' whether the same be of the wide or narrow dimension according to the size of quoin which was required to be used. But preferably, the mentioned shoulder extends circumferentially of the block whereby the implement can obviously be applied to a space a' having either the wide or narrow dimension and whether located at the left-hand or right-hand end of the quoin.

Having thus fully described my invention what I claim is:

1. A manipulating implement for sliding a printing form composed of a chase within which is held a sheet of type by at least one quoin of the double wedge type, the wedge confronting face of each wedge of the quoin having a longitudinal tongue, said implement comprising an upright block substantially in the form of a parallelopiped oblong in plan, the block having one of its dimensions in plan substantially equal to the height of the risers of the wedges of the quoin, at least one of the vertical faces of the block normal to said direction having an upwardly facing shoulder so located as to be slideable under the tongue on the exposed end of one wedge of the quoin, a substantially vertical stem pivotally connected to the top of the block, the stem being rotatable about a vertical axis, and a transversely extending handle connected to the stem at a point spaced from the block.

2. A manipulating implement for sliding a printing form composed of a chase within which

is held a sheet of type by at least one quoin of the double wedge type, the wedge confronting face of each wedge of the quoin having a longitudinal tongue, said implement comprising an upright block substantially in the form of a parallelopiped oblong in plan, the block having a first, longer one of its dimensions in plan substantially equal to the height of the risers of the wedges of a large quoin and having a second, shorter one of its dimensions in plan substantially equal to the height of the risers of the wedges of a small quoin, at least two of the upright sides of the block which adjoin each other having upwardly facing shoulders, said shoulder on the long side being so located as to be slideable under the tongue on the exposed end of one wedge of a small quoin, said shoulder on the short side being so located as to be slideable under the tongue on the exposed end of one wedge of a large quoin, a substantially vertical stem pivotally connected to the top of the block, the stem being rotatable about a vertical axis, and a transversely extending handle connected to the stem at a point spaced from the block.

3. A manipulating implement for sliding a printing form composed of a chase within which is held a sheet of type by at least one quoin of the double wedge type, the wedge confronting face of each wedge of the quoin having a longitudinal tongue, said implement comprising an upright block substantially in the form of a parallelopiped oblong in plan, the block having a first, longer one of its dimensions in plan substantially equal to the height of the risers of the wedges of a large quoin and having a second, shorter one of its dimensions in plan substantially equal to the height of the risers of the wedges of a small quoin, each of the upright sides of the block having a horizontal shoulder thereon, said shoulders forming a continuous shoulder about the block, the shoulders on the long faces being so located as each to be selectively slideable under the tongue on the exposed end of one wedge of a small quoin, the shoulders on the short faces being so located as each to be selectively slideable under the tongue on the exposed end of one wedge of a large quoin, a substantially vertical stem pivotally connected to the top of the block, the stem being rotatable about a vertical axis, and a transversely extending handle connected to the stem at a point spaced from the block.

4. A manipulating implement for sliding a printing form composed of a chase within which is held a sheet of type by at least one quoin of the double wedge type, the wedge confronting face of each wedge of the quoin having a longitudinal tongue, said implement comprising an upright block substantially in the form of a parallelopiped oblong in plan, the block having a first, longer one of its dimensions in plan substantially equal to the height of the risers of the wedges of a large quoin and having a second, shorter one of its dimensions in plan substantially equal to the height of the risers of the wedges of a small quoin, each of the upright sides of the block having a horizontal groove therein, said grooves communicating with each other, whereby a shoulder is formed on each such face, the shoulders on the long faces being so located as each to be selectively slideable under the tongue on the exposed end of one wedge of a small quoin, the shoulders on the short faces being so located as each to be selectively slideable under the tongue on the exposed end of one wedge of a large quoin, a substantially vertical stem pivotally connected

to the top of the block, the stem being rotatable about a vertical axis, a generally horizontally extending extension connected to the upper end of the vertical stem, and a transversely extending handle connected to the extension at a point spaced from the vertical stem.
